(57) **CLAIM**

We claim the ornamental design for a target-illuminating aiming device, as shown and described.

DESCRIPTION

FIG. 1 is a perspective view of the target-illuminating aiming device in an assembly in accordance with our invention;

FIG. 2 is a rear view of the target illuminating aiming device;

FIG. 3 is a bottom view of the target illuminating aiming device;

FIG. 4 is a right side view of the target illuminating aiming device;

FIG. 5 is a top view of the target illuminating aiming device;

FIG. 6 is a front side view of the target illuminating aiming device; and,

FIG. 7 is a left side view of the target illuminating aiming device.
